United States Patent Office

Des. 218,116

Patented July 21, 1970

218,116

DISHWASHER

Roger L. Crispell, Bloomfield Hills, Donald A. Schneider, Birmingham, and Gordon W. Severson, Royal Oak, Mich., assignors to General Motors Corporation, Detroit, Mich., a corporation of Delaware

Filed Feb. 26, 1969, Ser. No. 15,923

Term of patent 14 years

Int. Cl. D15—07

U.S. Cl. D49—1

Fig. 1

Fig. 2

Fig. 3

FIG. 1 is a front elevational view of a dishwasher having a slant top and downwardly inclined panel located in front of and below the top;

FIG. 2 is a side elevational view taken along the line 2—2 of FIG. 1 looking in the direction of the arrows; and

FIG. 3 is a top elevational view taken along the line 3—3 of FIG. 1 looking in the direction of the arrows.

We claim:

The ornamental design for a dishwasher, as shown and described.
